US00D674123S

(12) **United States Design Patent**
Yonash

(10) **Patent No.:** **US D674,123 S**
(45) **Date of Patent:** **** Jan. 8, 2013**

(54) **CEILING TILE**

(75) Inventor: **Richard F. Yonash**, Graton, CA (US)

(73) Assignee: **Empire West, Inc.**, Graton, CA (US)

(**) Term: **14 Years**

(21) Appl. No.: **29/404,723**

(22) Filed: **Oct. 25, 2011**

(51) LOC (9) Cl. **25-01**

(52) U.S. Cl. **D25/157**

(57) **CLAIM**

I claim the ornamental design for a ceiling tile, as shown and described.

DESCRIPTION

FIG. 1 is a front, top and left perspective view of the ceiling tile showing my new design;

FIG. 2 is a front elevational view thereof;

FIG. 3 is a rear elevational view thereof;

FIG. 4 is a right side view thereof whereby each other side view is identical to the side view of FIG. 4;

FIG. 5 is a cross-sectional view taken along section line 5-5 of FIG. 2;

FIG. 6 is an enlarged right end view of FIG. 5;

FIG. 7 is a front, top and left perspective view of the ceiling tile showing a second embodiment of my new design;

FIG. 8 is a front elevational view of the embodiment of FIG. 7;

FIG. 9 is a rear elevational view of the embodiment of FIG. 7;

FIG. 10 is a right side view thereof whereby each other side view is identical to the side view of FIG. 10;

FIG. 11 is a cross sectional view taken along line 11-11 of FIG. 8; and,

FIG. 12 is an enlarged right end view of FIG. 11.
